UNITED STATES PATENT OFFICE.

HENRY P. HAMILTON, OF TWO RIVERS, AND JULIUS HAMACHECK, OF MANITOWOC, WISCONSIN, ASSIGNORS TO THE HAMILTON MANUFACTURING COMPANY, OF TWO RIVERS, WISCONSIN, A CORPORATION OF WISCONSIN.

MACHINE FOR DRESSING WOODEN BLOCKS TO THICKNESS.

No. 833,163.

Specification of Letters Patent.

Patented Oct. 16, 1906.

Application filed May 18, 1905. Serial No. 260,958.

To all whom it may concern:

Be it known that we, HENRY P. HAMILTON, a resident of Two Rivers, and JULIUS HAMACHECK, a resident of Manitowoc, in the county 5 of Manitowoc, State of Wisconsin, citizens of the United States, have invented certain new and useful Improvements in Machines for Dressing Wooden Blocks to Thickness, of which the following is a specification.

10 This invention relates to machines for dressing wooden blocks to thickness, and relates particularly to machines for dressing blocks to thickness which are to be used in the manufacture of what are known as "end- 15 wood" type, said machines being commonly known as "type-high" machines.

End-wood type as is generally known are type carved or stamped in the surfaces of blocks of wood, usually maple, cut crosswise 20 of the grain, surfaced and polished on one side and dressed to thickness on the other, the type being cut or stamped and receiving the impression in printing lengthwise of the grain of the wood instead of crosswise of the 25 grain, as in other forms of wood type.

In the preparation of the blocks from which end-wood type is made the usual practice is to first surface and polish the sides of said blocks on which the letters are to be 30 formed and then to dress them to thickness on the opposite side in a suitable machine for the purpose, which, as stated, is commonly known as a "type-high" machine, by placing them on the movable bed of said machine 35 with their finished faces down and then imparting movement to said movable bed to cause said blocks to pass under the cutter of said machine.

When the first step, the surfacing and polishing of the blocks, is done by machinery, it is found that the blocks are liable to warp, particularly if any considerable length of time elapses between the surfacing and polishing of the blocks and the dressing of them 45 to thickness on the back in the type-high machine, said warping being probably due to the heating of the blocks in surfacing and polishing the same and the subsequent cooling thereof. It is found in practice that this 50 warping usually occurs in the form of "dish-

ing" of the blocks at the centers thereof and that the variation in the thickness of said blocks at their centers and edges due to such dishing is frequently several thousandths of an inch, the dishing and consequent variation 55 in the thickness of the blocks depending upon the size of said blocks, being comparatively slight in small blocks and much greater in larger blocks. The variation in the thickness of the blocks necessarily produces a corresponding variation in the length or height of the finished type made therefrom and which produces an uneven impression in printing from said type.

The object of the present invention is to 65 provide means in a type-high machine whereby the blocks of wood will be held flat upon the bed of the machine when being presented to the cutter thereof, thus overcoming the effect of the warping or dishing of said blocks 70 and producing blocks of practically uniform thickness. Thus when said blocks are subsequently cut into small blocks which are to receive the individual letters and other characters said smaller blocks will be of the same 75 thickness and the type made therefrom of the same height. Experience has shown that the variation in the height of type made from blocks finished in a type-high machine 80 equipped with or embodying our improvements does not exceed one one-thousandth of an inch and that the impressions therefrom in printing are, so far as the eye can detect, absolutely uniform.

Broadly stated, our invention consists of a 85 pressure-roller supported above the bed of the machine so as to be movable toward and from the same and which is designed and adapted for applying pressure to a block of wood supported upon the bed of the machine 90 closely adjacent to the point at which said block is presented to the cutter of the machine, together with means for urging said pressure-roller toward the bed of the machine with a force corresponding to the pressure 95 which it is desired to exert upon said blocks. Preferably, also, said pressure-roller is supported so as to be movable transversely of the machine-bed to provide for adjusting the same centrally of the blocks of 100

wood. Our improved pressure device also preferably comprises suitable means to limit the approach of said pressure-roller to the bed of the machine and for stopping the drop of said pressure-roller without jar as it runs off from the block of wood or is otherwise suddenly released at a point above its point of nearest approach to the bed of the machine.

10 Our invention also consists of the various other features, combinations of features, and details of construction hereinafter described and claimed.

15 In the accompanying drawings, in which a pressure device of our invention is fully illustrated as applied to a type-high machine, Figure 1 is a partial top plan sectional view of a type-high machine, showing our improved pressure device in top plan view applied thereto. Fig. 2 is a partial sectional side elevation thereof on the line 2 2 of Fig. 1. Fig. 3 is a partial sectional elevation thereof on the line 3 3 of Fig. 1. Fig. 4 is a sectional elevation on the line 4 4 of Fig. 1, and Fig. 5 is a sectional view on the line 5 5 of Fig. 3.

20 Referring now to the drawings, A designates the stationary bed or frame of a type-high machine; B, the movable bed or carriage thereof; C, the cutter-head; D, the cutter secured thereto, and E the cutter-shaft, all of which may be of any desired or approved construction.

25 The machine is represented as operating upon a block of wood, (shown at F,) which is secured upon the movable bed B of the machine, with its surfaced and polished side down, by means of dogs or clamps f, the heads of which slidably engage transverse T-slots f' in said movable bed B and which are adjustable in said slots to effect engagement thereof with the blocks F by means of screws f'', all in the usual manner.

30 Revolubly supported above the movable bed B of the machine closely adjacent to the point at which the block F is presented to the cutter D and in such manner as to be movable toward and from the bed of the machine is a roller 1, said roller being also preferably movable transversely of the machine to provide for adjusting it centrally of a block upon which the machine is operating at a given time.

35 In the preferable construction shown the roller 1 is mounted on a shaft 2, secured against rotation in suitable bearings in a frame 3, provided with trunnions 4, which are fitted to and freely revoluble in suitable bearings formed at the upper ends of brackets or standards 5, bolted to the stationary bed A 40 of the machine and which extend upwardly outside of and above the movable bed B. To provide for adjusting the pressure-roller 1 centrally of a given block, the portion of said shaft 2 which forms the journal for said 45 roller is made materially longer than the

thickness of said roller where it engages said shaft, is fitted thereto so that it may be freely movable lengthwise thereof—that is, transversely of the bed B.

50 The shaft 2 is disposed out of line with or eccentric to the axis of the trunnions 4 of the frame 3, which carries said shaft 2. Rotary movement of said frame 3 upon its trunnions will thus operate to impart movement to said roller 1 toward and from the bed of the machine as said frame is moved in one direction or the other.

55 The roller 1 is normally urged toward the bed of the machine by means of a desired force applied to the frame 3. As shown, this force is exerted upon said frame 3 by means of a lever 6 applied to said frame, which carries a weight 7, preferably in such manner as to be adjustable lengthwise thereof to provide for varying the force applied to the frame 3, and thus the pressure exerted upon the blocks F by the roller 1. As shown, the lever 6 is secured in a suitable groove formed in an arm 8 on a hub 9, keyed to the projecting end of a trunnion 4 of the frame 3. In practice it is found that a pressure of approximately three hundred pounds exerted on the blocks F will operate to overcome the warping or dishing thereof, so as to force the under side or surface thereof into contact with the bed of the machine.

60 In practice desired play or movement of the pressure-roller 1 is secured with an eccentricity of about two and one-half inches of the shaft 2 relatively to the trunnions 4 of the frame 3, and with this relation desired pressure on the blocks F can be secured by means of a weight of sixty pounds carried on the lever 6 at approximately twelve and one-half inches from the axis of the trunnions, and in particular cases this pressure can be increased or decreased, as may be desired, by changing the point of application of the weight 7 to the lever 6.

65 The roller 1 is adapted to be raised out of the path of a block F as said block approaches the cutter E by means of a foot-lever 10, pivoted to a suitable support, as a floor bracket or standard 11, one end of which is connected to the lever 6 by means of a rod or bar 12.

70 The roller 1 is preferably applied as close as practicable to the cutter E, and to prevent said roller from dropping down into contact with said cutter a suitable stop is provided which limits the downward movement of said roller, said stop being preferably of such nature that a yielding resistance will be offered to the downward movement of said roller before the same is positively stopped, said yielding resistance or cushion operating to check the downward movement of said roller and to effect the stopping thereof without jar. In the preferable construction shown the downward movement of said

roller 1 is checked and stopped in the following manner: Secured to the projecting end of the trunnion 4 other than that to which the lever 6 is applied and in substantially the same manner is a lever 13, the outer end of which is connected by a rod 14 to the piston 15 of a dash-pot, the cylinder 16 of which is secured in fixed position to the side of the main bed or frame A of the machine.

10 Formed in the side of the cylinder 16 of the dash-pot at such a distance above the bottom thereof that it will be uncovered when the piston 15 is raised a distance corresponding to the elevation of the roller 1 when resting upon a block F of minimum thickness is a vent hole or opening 17. Thus as long as there is a block F in the machine upon which the pressure-roller 1 rests air may freely enter the dash-pot below the piston 15, so as to 15 allow unrestricted movement of said piston, and thus of the frame 3 and the roller 1, under the influence of the weight 7. As soon, however, as the roller 1 runs off from the block F said roller can fall only a very short 20 distance before the piston 15 will close the vent-hole 17, thus forming an air-cushion beneath said piston, which will offer a yielding resistance to the further downward movement of the roller 1 and will operate to 25 stop said roller gradually as the air in the dash-pot 16 gradually escapes past said piston or when the pressure in the dash-pot becomes great enough to counterbalance the weight 7. The bottom of the cylinder 16 of 30 the dash-pot forms a rigid stop which will operate to positively limit downward movement of the pressure-roller 1 when the under side of the piston 15 comes into contact therewith, and to provide for regulating the 35 lowermost position of said roller 1 the rod 14, which connects the piston 15 with the lever 13, is adjustable, so that by making the same longer or shorter the piston 15 will come into contact with the bottom of the dash-pot 10 at a higher or lower position of 40 said pressure-roller, as may be desired. To provide for adjusting the length of the rod 14 in the manner described, said rod is made in sections screwed together and adapted to be 45 secured in adjusted position by means of a suitable check-nut, and to provide for turning said rod relatively to the piston 15 in adjusting the same said rod is connected to said piston by means of a ball-and-socket joint 18, as clearly shown in Fig. 2 of the 50 drawings.

In order to break the vacuum in the dash-pot below the piston 15 when it is desired to raise the pressure-roller 1, and thus remove 55 all resistance to the raising of said roller due to this cause, said dash-pot is provided with a check-valve in its bottom which is adapted to open when the piston of the dash-pot is raised and will be closed when and as said 60 piston is forced down. As shown, said

check-valve consists of a ball 19, provided with a suitable seat 20 at the inner end of an opening 21, formed in the bottom of a cup or pocket 22 in the bottom of the cylinder 16 of the dash-pot. As shown, also, said ball 19 is 65 normally held to its seat by a light spring 23, inserted between said ball and a shoulder formed by a bushing 24, screwed into the upper end of the pocket 22.

When the piston 15 is above the vent hole 70 or opening 17, in which position no resistance is offered to the movement of said piston 15, said piston will operate as a weight to exert a downward pressure on the roller 1 in the same manner as the weight 7, thus rendering 75 it possible to distribute the gross total weight necessary to exert the desired pressure on the blocks F between said piston 15 and the weight 7.

We claim as our invention—

1. In a machine of the type described, the combination of a movable bed, means for securing a block of wood or other work upon said bed, a cutter and a pressure device for applying pressure to said block of wood or 80 other work while being presented to the cutter, said pressure device comprising a pressure-roller revolvably mounted above the bed of the machine in position to pass substantially across the center of the work, said 85 pressure-roller having a tread for engaging the work much narrower than the width of the work whereby the full force of said pressure-roller will be exerted substantially at the center of the work.

2. In a machine of the type described, the combination of a movable bed, means for securing a block of wood or other work upon said bed, a cutter and a pressure device for applying pressure to said block of wood or 90 other work while being presented to the cutter, said pressure device comprising a pressure-roller revolvably mounted above the bed of the machine in position to pass substantially across the center of the work, said 95 pressure-roller having a tread for engaging the work much narrower than the width of the work whereby the full force of said pressure-roller will be exerted substantially at the center of the work and said roller being freely 100 movable transversely of the bed of the machine to provide for adjusting the same centrally of the work.

3. In a machine of the type described, the combination of a movable bed, means for securing a block of wood or other work upon said bed, a cutter and a pressure device for applying pressure to said block of wood or other work, said pressure device comprising a frame rotatably mounted above the bed of 110 the machine, a shaft secured in said frame eccentrically to the axis about which said frame is rotatable and a pressure-roller mounted to rotate freely on said shaft in position to pass substantially across the center 115 120 125 130

of the work, said pressure-roller having a tread for engaging the work much narrower than the width of the work whereby the full force of said pressure-roller will be exerted substantially at the center of the work.

4. In a machine of the type described, the combination of a movable bed, means for securing a block of wood or other work upon said bed, a cutter and a pressure device for applying pressure to said block of wood or other work, said pressure device comprising a frame rotatably mounted above the bed of the machine, a shaft secured in said frame eccentrically to the axis about which said frame is rotatable, and a pressure-roller mounted to rotate freely on said shaft, said pressure-roller having a tread for engaging the work much narrower than the width of the work and the portion of said shaft which forms the journal for said roller being longer than the thickness of said roller where it engages said shaft to provide for moving said roller laterally to adjust the same centrally of the work.

5. In a machine of the type described, the combination of a movable bed, means for securing a block of wood or other work upon said bed, a cutter and a pressure device for applying pressure to said block of wood or other work while being presented to the cutter, said pressure device comprising a frame rotatably mounted above the bed of the machine, a pressure-roller revolvably mounted on said frame, a lever applied to said rotatable frame, a dash-pot and a rod which connects the piston of said dash-pot with said lever at a distance from the axis of said rotatable frame equal to several times the eccentricity of said pressure-roller.

6. In a machine of the type described, the combination of a movable bed, means for securing a block of wood or other work upon said bed, a cutter and a pressure device for applying pressure to said block of wood or other work while being presented to the cutter, said pressure device comprising a pressure-roller revolvably mounted above the bed of the machine in position to pass substantially across the center of the work, said pressure-roller having a tread for engaging the work much narrower than the width of the work whereby the full force of said pressure-roller will be exerted substantially at the center of the work, and stops which limit

the approach of said pressure-roller to the bed of the machine.

7. In a machine of the type described, the combination of a movable bed, means for securing a block of wood or other work upon said bed, a cutter and a pressure device for applying pressure to said block of wood or other work while being presented to the cutter, said pressure device comprising a frame rotatably mounted above the bed of the machine, a pressure-roller revolvably mounted on said frame eccentrically to the axis of rotation of said frame, a lever applied to said rotatable frame, a dash-pot, a rod which connects the piston of said dash-pot with said lever at a distance from the axis of said rotatable frame equal to several times the eccentricity of said pressure-roller, and rigid stops which define the lowest position of said pressure-roller, the relation being such that an air-cushion will be formed in said dash-pot prior to contact of said rigid stops.

8. In a machine of the type described, the combination of a movable bed, means for securing a block of wood or other work upon said bed, a cutter and a pressure device for applying pressure to said block of wood or other work while being presented to the cutter, said pressure device comprising a frame rotatably mounted above the bed of the machine, a pressure-roller revolvably mounted on said frame eccentrically to the axis of rotation of said frame, a lever applied to said rotatable frame, a dash-pot and a rod which connects the piston of said dash-pot with said lever at a distance from the axis of said rotatable frame equal to several times the eccentricity of said pressure-roller, the relation being such that a rigid portion of the piston of said dash-pot will strike a rigid portion of the cylinder of said dash-pot at a predetermined point in the downward movement of said pressure-roller.

In testimony that we claim the foregoing as our invention we affix our signatures, in presence of two subscribing witnesses, this 8th day of May, A. D. 1905.
